DONALD W. RANDOLPH AND TAINA G. McDUGAL, OF FLINT, MICHIGAN, ASSIGNORS TO
A C SPARK PLUG COMPANY, OF FLINT, MICHIGAN, A COMPANY OF MICHIGAN

SPARK PLUG

Application filed November 5, 1928. Serial No. 317,307.

This invention relates to electrical devices, such as spark plugs, which are subjected to heat and wherein fused quartz or other similar material is employed as an insulator.

Since fused quartz is not only one of the best known non-conductors of electricity but also has a very low co-efficient of expansion, whereby it may be exposed to sudden changes of temperature without liability of fracture, it is highly desirable for use as an insulator core in the manufacture of spark plugs. However, fused quartz is diathermanous to radiations from a source of high temperature such as is present in the combustion chamber of an internal combustion engine, and its resistance to the passage of such heat rays is so low that it does itself not become hot. Being an excellent medium for the transmission of radiated heat rays, the use of fused quartz as a spark plug insulator obviously allows the radiated heat rays, emanating from the explosions in the engine cylinder, to be transmitted to and absorbed by certain upper parts of the plug, as for instance, the terminal connector nut as well as the current conducting lead wire, which, therefore, become intensely hot. In a comparatively short time such heat will have a destructive effect on these parts and it is one of the objects of the present invention to provide a spark plug wherein the absorption of radiant energy transmitted through the insulator core of high heat transmissibility by the upper and associated parts of the plug is effectually prevented. To this end there is contemplated the provision of a mirror-like surface to reflect or dissipate the heat rays before they are taken up by the top parts of the plug.

The invention will be more fully comprehended upon reference to the accompanying drawing wherein Fig. 1 is a vertical sectional view of a spark plug embodying the present invention, Fig. 2 is a vertical sectional view of a spark plug illustrating a modification; Fig. 3 is a sectional view of the upper portion of the insulator core shown in Fig. 2; and Fig. 4 is a detail view partly in section of the reflector employed in Fig. 2.

In the accompanying drawing the refer-

ence character 1 indicates the outer shell having a screw-threaded portion for engagement within the customary spark plug-opening in the cylinder head of an internal combustion engine. Within the shell is contained the insulator core 2 of fused quartz or other similar diathermanous material, the packing rings or gaskets 3 and 4 serving to prevent leakage between the insulator core and shell, and the flange 5 of the shell being crimped or spun over to maintain the parts in assembled relationship. Surrounded by the insulator core is a central electrode or current-conducting wire 6, the lower end of which is spaced from the electrode 7 carried by the shell to form a sparking gap, and the upper end of the electrode 6 being provided with a terminal tip to receive a suitable connector, such as the nut 8 for fastening the current conducting lead wire thereto. Interposed between the connector element and the top of the insulator core is a washer 9, the under side of which, or that side contacting with the top of the insulator core, having a burnished or plated surface for reflecting heat waves away from the upper portions of the plug. Polished brass is an excellent reflector of heat and if desired the washer 9 may be made of brass and its under surface highly polished. The heat waves emanating in the engine combustion chamber and which travel in straight lines are transmitted through the insulator core to the upper portion of the plug until they strike the mirror-like surface of the under side of the washer 9 when they are reflected back to the engine cylinder. For illustrative purposes the path of the heat rays is indicated in the drawing by the double-headed arrows marked 10.

In Fig. 2 the insulator core 11 inclosing the central electrode 12 and carried by the shell 13, is provided with a concave recess in its top surface in which is seated the concavo-convex or conical washer 14, whose under surface is highly polished to provide a reflecting surface for the heat rays. In this case, the radiations from the combustion chamber are transmitted through the insulator along the path indicated by the arrows 10.

15, striking the inclined reflector surface, and being thrown laterally beyond the body of the insulator.

From the above description, it will be apparent that there has been provided a spark plug wherein the heat rays are reflected away from the upper metallic parts of the plug, and since the rays are not absorbed by such parts, the parts do not become hot and are thus saved from deterioration and damage.

10 While the invention has been described more or less specifically, it is to be understood that the invention is not limited to the exact details shown, but that such modification 15 may be made as come within the scope of appended claims.

We claim:

1. In a spark plug for engines, a connector terminal, an electrical insulator core of 20 diathermanous material and a reflector interposed between the connector terminal and core to reflect radiant energy and prevent its absorption by the terminal.

2. In an electrical device, a current conductor, an insulator therefor of a material 25 transparent to heat rays, a connector associated with said conductor and a reflecting surface between the connector and said insulator to reflect heat waves away from the connector.

30 3. In a device of the character described, a member of relatively low resistance to the transmission of heat rays, a member of relatively high resistance to heat transmission 35 positioned adjacent the first mentioned member, and means interposed between said members to reflect heat radiations transmitted thru said first mentioned member.

4. In a spark plug, an electrode, an electrical insulator surrounding the electrode and 40 having a relatively low resistance to heat radiations, a connector device for said electrode adjacent the upper end of the insulator and a heat wave reflector interposed between the insulator and connector device.

45 5. In a spark plug, an insulator core transparent to heat radiations, an electrode extending thru the core, and having a connector device located beyond the core, a member 50 interposed between the connector device and core and having a reflecting surface abutting the core and extending angularly to the axis thereof to reflect heat radiations transmitted thru the core and prevent their absorption by the connector device.

55 6. In a spark plug, an electrode having a connector tip, an insulator core transparent to heat radiations, surrounding the electrode and having a concave top surface directly beneath the connector tip and a convex washer 60 extending into the concavity having a mirror-like surface abutting the top surface of the core, whereby heat radiations transmitted thru the core and impinging on said mirror-like surface are reflected angularly outside

the core without reaching the connector tip.

7. In a spark plug, an insulator core of fused quartz, a connector part at the upper end of the core, and a reflecting surface at the top of the core and below the connector part.

8. In a spark plug, a central electrode, an insulator of fused quartz surrounding the electrode, a connector at the end of the electrode beyond the core, and a reflecting surface interposed between the connector and insulator core.

* In testimony whereof we affix our signatures.

DONALD W. RANDOLPH.
